UNITED STATES PATENT OFFICE

2,156,163

VENETIAN BLIND

Robert C. Pierce, Niles, Mich., assignor to National Standard Company, Niles, Mich., a corporation of Michigan

Original application September 19, 1935, Serial No. 41,199. Divided and this application March 6, 1937, Serial No. 129,296

1 Claim. (Cl. 156—17)

This invention relates to the manufacture of Venetian blinds or the like, and more especially to the slats forming the transverse elements or shutters of the blinds, and to an improved method of making such slats.

An object of the invention is to provide durable, light-weight, and inexpensive slats or shutter elements for Venetian blinds, of such a structure that they are translucent, and preferably with an attractive pattern outlined against light transmitted therethrough. I prefer to use as the base or blank, from which the slat is made, a blank of wires associated to form a mesh with relatively large open spaces, giving the desired pattern, and which is preferably made by expanding widthwise a flat braid of wire.

The edges of the blank are bound, and the blank is then dipped in non-metallic material which is of a translucent nature and which when dried forms a protective coating for the wires and for the binding material, and which bridges across the open spaces between the wires of the blank to form a tough film therebetween.

The above and other objects and features of the invention will be apparent from the following description of the slats and method of forming them illustrated in the accompanying drawing, in which:

Figure 1 is a top plan view of part of one of the slats made from expanded braid, with parts of the edge bindings and of the non-metallic coating broken away to show underlying structure;

Figure 2 is a section therethrough on the line 2—2 of Figure 1;

Figure 3 is a view similar to Figure 1, but showing a slat made from woven wire cloth; and

Figure 4 is a plan view of the finished slat.

The slat herein illustrated as the preferred embodiment of my invention is made from a wire tape 10, preferably braided as shown in Figure 1 except that the meshes are not at that time spread out and opened, i. e. the braid consists of a compact flat structure comprising a number of wires 12 each of which extends the full length of the braid and which extend alternately over and under each other diagonally of the braid as appears in Figure 1.

The first step in the manufacture of the shutters from such a braid is the spreading of the wires 12 apart, to form relatively large spaces or meshes 16 therebetween; the next step is ordinarily to crimp sheet metal U-section binders 18 along the edges; and the braid is then cut in sections or blanks. If desired, the ends may also be bound similarly with crimped U-section binders

20. The coating material is then applied, and suitable openings 22 (protected by eyelets or the like) are formed for the cords by which the blinds are operated.

The coating material may be any suitable material which can be mixed with a solvent to such a consistency that it will form a film 20 covering the wires and the edge bindings and bridging across the spaces or meshes 16 between the wires, as shown in Figures 1 and 2, and which will dry to form a tough, thin, translucent, durable film. One example might be: 106 pounds cellulose acetate (or nitrate), 27 gallons toluol, 13½ gallons butyl acetate, 4½ gallons butyl alcohol, and 2 gallons dibutyl phthalate. Or a simple solution of nitrocellulose in butyl lactate may be used, sufficient of the solvent being used to make a solution as thin as will bridge across the spaces 16 between the wires. Various other lacquers and the like may be used, usually consisting of various mixtures of cellulose esters or other compounds with plasticizer or a resin or both, and a solvent such as butyl lactate, butyl alcohol, ether, acetone, and the like. The coating, when applied, forms a continuous impervious coating for the wires and for the edge binders and bridges integrally across the spaces between the wires, the binders and wires being imbedded in the material of the coating.

The shutter or slat so made, after the drying 30 of the translucent film, may if desired be additionally treated by brushing or spraying or otherwise applying on one or both of its sides a further coat containing, for example, cellulose acetate and a pigment or dye or other coloring 35 material, with a relatively small amount of solvent which is driven off in drying.

By selecting these outer coatings of suitable different colors, the shutter will appear one color on one side (viewed by reflected light) and a different (reflected) color on the other side, and will be a still different (combination) color when viewed by transmitted light. The wire pattern adds to the pleasing effect of the design.

If desired, the shutter may be provided with 45 differently colored intermediate films of the above-described materials. These are not visible from either side by reflected light, but modify the color of the transmitted light. Such intermediate coatings may be of one solid color, or 50 may be applied in various patterns or figures. In some cases these intermediate coatings may be merely a solution of coloring material in a solvent such as butyl lactate.

Some of the advantages of the invention may 55

be obtained by making shutters by applying coating materials, in the manner described, to blanks or sections 162 cut diagonally from sheets of woven wire cloth, as illustrated in Figure 3.

- 5 While a particular method, and particular forms of shutters, have been described above, it is not my intention to limit the scope of the invention by that description, or otherwise than by the terms of the appended claim. The present 10 application is a division of my application No. 41,199, filed September 19, 1935.

I claim:

A translucent element for a blind or the like comprising an elongated blank of wires associated to form a mesh with relatively large open spaces, 5 bindings for the edges of the blank, and a continuous impervious coating for the wires and said bindings which bridges integrally across said spaces, said bindings and said wires being imbedded in the material of said coating.

10
